SOLE TRIMMING MACHINE

Charles L. Flindt, San Jose, Calif.

Application March 1, 1944, Serial No. 524,543

8 Claims. (Cl. 12—85)

1

This invention relates to machines for rounding and trimming the soles of shoes.

The objects of this invention are first, to produce a machine which in one operation on a shoe sole, will produce a result equal to that now produced in shoe factories by the combined use of the rough rounder and trimmer; second, to improve and simplify that branch of shoe sole trimming which employs a draw stroke of a knife saw in severing the soles as distinguished from the rough rounder which cuts the sole with a chisel chopping action.

The drawings and specifications will clearly point out a faster operating machine, a less complicated machine and a machine producing a smoother trim in the output than other machines have made possible.

Fig. 1 is a front view of the essential features of the machine.

Fig. 2 is a top view of the circular knife and its bearings.

Fig. 3 is a top view of the sole gauger and its bearing.

Fig. 4 is a detached knife blade rolled out flat.

Fig. 5 is a detail showing operating position of the knife relative to the shoe sole.

Fig. 6 is an enlarged detail showing an angle knife for removing the feather edge of a trimmed sole.

Fig. 7 is a side view of a blade and its mountings.

References will be made in these pages to the patent of Flindt, U. S. Patent No. 2,288,897, July 7, 1942.

The base 20 together with its legs (not shown) supports the machine. The cutter 2 of Fig. 2 is fitted around shaft 4 which rotates in ball bearings 41 in journals 14—14. These journals 14 are supported in their positions in proper relation with machine base 20, by block 37 attached thereto.

Sole cutter

I am aware that previous to this application flat circular blades have been used to trim soles; the principal objection to this custom has been the impossibility to trim with accuracy in the curve of the shank of the sole for the reason that a flat circular blade cannot follow in a curved cut without distorting the work and producing an inaccurate result. By the use of a concave circular blade, I am able to cut in a curved line with accuracy and smoothness which is a major objective in this application.

There are modifications of a concave blade which will obtain the same result providing clear-

5
2
ance is provided behind the rim or cutting edge of the blade for preventing a binding and interference of the blade 2 with sole 32 as the shank curve is being cut (see Fig. 5).

Work holding

When the operator of the machine trims a shoe sole he stands in front of Fig. 1, with the tread of the shoe sole resting on block 17 and ball 18, and he bears the upper of the shoe adjacent the sole against hood 3. In order to take the various thicknesses of soles, cord 28 which connects pivot block 8 and pedal (not shown), enables the operator to depress the pedal sufficient to barely allow clearance of the shoe bottom between block 17 and the lower edge of the hood, and when in the desired position the nut 26 is adjusted to maintain the said clearance. The bolt 25 passes through a larger hole in base 20 and seats rigidly 15 in pivot block 8 and has a spring 27 encircling the bolt which controls the degree of pressure placed on the welt of the shoe bottom. The block 8 it will be seen is concentric with the drive of the blade, for it pivots around the blade carrier axis 4. Thus it will be seen that even though 20 a very thick sole must be trimmed the relation of the hood 3 to that of the blade remains the same whether the soles are thick or thin.

30

Sole extension

The rotary sole gauging hood 3 is nicely balanced to run freely in its ball bearings 39 and because it is contacted by the shoe upper at a point near central with the rim of the blade, a minimum of resistance is encountered to the work feeding operation. These features have outstanding value at this time when so many of the shoe styles include uppers with heavy seams which 35 extend down to the welt and project enough to prevent an ordinary sole extension gauge from operating without danger of stalling at such projection. The rotary sole gauging hood of this invention rides over such seams without interference therefrom.

The hood is bell shaped and is turned in a true circle with a very thin bell shaped rim and one piece stem; this stem is journaled in ball bearing 50 holders 6 between collars 7 and 7, and the said holders bolt rigidly to member 9 which in turn pivots around bolt 10 that seats in pivot block 8.

When the machine operator desires to gauge the sole extension which he wants to have remain on the shoe, he loosens nut 12 on bolt 36 and 55 moves member 9 to the left as much as desired;

the slot 13 in member 9, permitting movement around pivot 10.

Operation

The trimming is done with a cup shaped blade 1, having a cutting edge at near right angles to the curve of the blade; it is mounted on a blade carrier 2, and in Fig. 1 is pictured with a smooth cutting edge which is best for some types of rubber cutting. In Fig. 2 the carrier 2 and blade are turned in one piece and the teeth are bevel sharpened which are the most effective when cutting leather soles.

As indicated in Fig. 2, the blade when in motion passes sole support block 17 in close contact relation; it will also be noted that the teeth 34 each have an edge which extends at near right angles to the path of the blade and these edges pass the block 17 at near the same plane as the surface of the block. My experience has taught me that when these said right angle edges of the teeth pass the work support 17 at the same level as the surface of the support a neutral effect occurs as regards feeding of the work, but when a slightly acute angle is given to these said edges and the support 17 is at a level plane, a pull is exerted on the work and a positive assist to feeding occurs. Thus for the reason that the edge nearest the periphery of the blade hits the work first (the movement being counterclockwise), a drag is created on the work towards the cutter in proportion to the degree of acute angle built into the teeth of the saw.

The block 17 is made of hard steel or similar material and fits the blade in order to insure close clearance of the blade past it and inasmuch as each of the said edges are bevel sharpened toward their outer circumference at a proper angle (somewhat as a saw is filed), a shearing effect of the work is produced as the teeth pass the block and it cooperates with the blade.

The outer edges of the teeth which together form the periphery of the blade, are in the form of a knife edge which insure a clean cut through the work. The spaces between the teeth permit easier and more effective feeding of the work for when in motion the resistance to the feeding operation is intermittently removed with the passing of each tooth alternating with an intermittent advance of the cutting edge in the cut being made.

Feeding

As before stated, hood 3 is adjusted to allow bare clearance of the work between it and the work support, according to the work and as the operator elects. Thus hand feeding of the work against the blade is made easy.

In Figs. 5 and 6, the blade carrier 2 is created with a recess and shoulder for receiving blade 1 of Fig. 4, which is made of spring tempered steel and lays out flat as shown when not coiled up for insertion into the carrier. The said shoulder receives the back or straight edge of the blade and screws 35 attach the blade to the carrier.

The blade is rotated counterclockwise on its ball bearings 14 and 14 by power through a V-belt over pulley 16 of Fig. 2. Thus as rotation proceeds the blade 1 of Fig. 4 contacts the work first with the narrow section and the blade advances in the cut with the passing of each wider section of the blade and an intermittent advance of the cutting edge in the work occurs when in movement, for the feeding of the work will operate to advance the work more when the narrow sections of the blade are opposing the work and

therefore the said wide sections of the blade will more effectively bite into the work than would be true were the entire periphery of the blade one smooth cutting edge.

Edge burnishing

The left edge of the blade carrier 2 and its blade which together engage the body of the sole, are polished to a high degree and the continuous rub against the cut edge produces not only a smooth edge but also a polished edge when cutting leather.

Edge thinning

Block 17, shown in Fig. 1 and in enlarged detail in Fig. 6 carries an angle knife 21 connected to stem 22 and held by screw 23; this knife removes or rather thins and rounds off the feather edge left by the circular knife at the bottom of the sole 32.

It will be seen in Fig. 2, that the blade and carrier 2, fit into a V-shaped slot in block 17. The fit is close in order that bare clearance is provided and accordingly the work is cut very clean as the blade passes the block. Therefore for most work the knife 21 can be removed but is desirable when a thinner edge is specified for the finished sole.

The container 30 holds a mixture of water with a small per cent of water soluble oil in it; this compound saturates wick 31 which contacts the blade to lubricate same and is especially valuable when the operator is trimming soles (rubber) for it enables smoother cutting and insures a sharp blade for a longer time.

It will be noted in Figure 1 that the position of work support 17 is located nearly central horizontally with the axis of the blade carrier. This is the preferred form, however, I do not wish to be limited to this arrangement for very good results are obtained when the work is presented to the blade for trimming at either the top or bottom of the blade. These different modifications do not change the essential characteristics of the blade which are covered in the claims in a broad form.

In the drawings of the patent previously referred to in these pages, it will be noted that an arcuate approach of the trimming blade toward the upper is an important part of the invention for this mechanical feature enables closer entry toward the arch of the shoe when the machine operator shapes the shank of the sole, than was true in former practice when the blade action was vertical.

In this present invention the sole support is positioned nearly central and at one side of the periphery of the blade. It will be noted that this arrangement established with a circular blade the desired arcuate approach toward the work featured by the said patent cited above, and also enables that the cut made in the work by the blade to more nearly approach a right angle to the tread surface of the shoe sole. As explained previously under the heading "Sole cutter" it is important that the shape of the blade behind the rim be such as to enable it to follow in the cut when the operator shapes the curves in the shank section of the shoe sole; of equal importance is the "arcuate approach toward the work," just above explained. By way of recapitulation these two features are repeated in order to emphasize their importance.

Having explained my invention what I claim and desire to secure by Letters Patent is:

1. The combination in a sole trimming ma-

chine of, sole supporting and holding devices, a rotary concavo-convex circular blade, a member having an edge located adjacent and extending parallel of the outside of the cutting rim of the blade in cooperative relation therewith, means for rotating the blade past the said cooperating edge for severing the excess overhang of a shoe bottom, and a guide interposed between the blade and the shoe upper for guarding the upper from possible damage by the blade.

2. The combination in a shoe sole trimming machine, of a concave rotary circular blade, a member with a cooperating edge contacting the blade to assist the blade as it passes it in severing the excess overhang of a shoe bottom, means for thinning the trimmed edge of the shoe bottom, means for determining the extent and uniformity of the sole extension left on the shoe bottom, and a guard contacting the upper of the shoe in position to protect same from possible blade damage.

3. The combination in a sole trimming machine, of a rotary concave circular blade, a series of teeth in the work engaging rim of the blade, a work support, and a cooperating edge in connection with the support located adjacent, and extending on both sides of the cutting rim of the blade to function as a work holder and to assist the teeth of the blade in creating a clean smooth cut of the work when the blade is rotated and the teeth pass the said edge.

4. The combination in a shoe sole trimming machine, of a rotary concave circular blade, a work support abutting the blade with an edge which cooperates with the blade in severing the sole extension of a shoe bottom, and means for assisting the operator of the machine in guiding the work against the blade and over the support in free moving relation comprising a guide mounted to contact the upper of the shoe during the trimming operation to insure a uniform sole extension remaining on the shoe bottom.

5. In a shoe sole trimming machine, the combination with sole supporting and holding means, of a concave circular saw shaped for enabling the trimming of the curves of the shank of a shoe bottom, means mounting the saw on an axis for rotation thereon with all points on the periphery of the saw equidistant from the said axis, means for contacting the upper of the shoe in position to protect same from injury liable from the saw, and a member located adjacent the blade and having one side thereof parallel to the cutting rim of the blade and forming a cooperating edge past which the saw is rotated for assisting the saw in severing the excess overhang of a shoe bottom.

6. The combination in a shoe sole trimming

machine, of sole supporting and guiding devices, a blade shaped in arcuate form and mounted to enable closer entry toward the shoe when the shank of the shoe sole is being trimmed, and a cooperating edge located adjacent and extending parallel the cutting rim of the blade in position to assist the blade in severing the excess overhang of a shoe sole when the blade moves past the said edge.

10 7. The combination in a shoe sole trimming machine, of sole supporting and guiding devices, a blade shaped in arcuate form and having a lateral edge and mounted to enable closer entry toward the arch of the shoe when the shank of the shoe sole is being trimmed, a cooperating edge located adjacent and extending parallel the cutting rim of the blade in position to assist the blade in severing the excess overhang of a shoe sole when the blade moves past the said edge, 15 and means for lubricating the cutting rim of the blade to facilitate cutting.

8. The combination in a shoe sole trimming machine, of sole supporting and guiding devices, a blade shaped in arcuate form and having a lateral edge and mounted to enable closer entry toward the shoe when the shank of the shoe sole is being trimmed, a cooperating edge located adjacent and extending parallel the cutting rim of the blade in position to assist the blade in trimming off the excess overhang of a shoe sole when the blade moves past the said edge, a guard in position for contacting the upper of the shoe to thereby hold the upper away from the path of the moving blade and possible injury therefrom, 25 and means for lubricating the rim of the blade to facilitate cutting.
